UNITED STATES PATENT OFFICE.

JULIUS FRIED, OF NEW YORK, N. Y.

DENTAL APPARATUS.

1,390,354.

Specification of Letters Patent. Patented Sept. 13, 1921.

Application filed December 26, 1918. Serial No. 268,358.

To all whom it may concern:

Be it known that I, JULIUS FRIED, a citizen of the United States, residing at New York, in the county of New York and State of New York, have invented certain new and useful Improvements in Dental Apparatus, of which the following is a specification.

This invention has relation to dental apparatus, and has for an object to provide a device adapted for attachment to the hand piece of a dental engine for the purpose of collecting in a single receptacle the particles which are driven off during the act of grinding porcelain teeth, gold crowns, etc. Another object of the invention is to provide an attachment for the purpose above set forth including means to partly inclose the grinding wheel which may be associated with the hand piece, and means for creating a vacuum in the vicinity of the grinding wheel whereby to collect all the particles which are driven off during the act of grinding porcelain teeth, gold crowns and the like and for depositing the particles in a single receptacle for a purpose to be presently noted.

A still further object of the invention is to provide an attachment for dental hand pieces embodying a shield to partly inclose the grinding wheel, a blower or the like for creating a vacuum, and means whereby the blower may be driven directly from the spindle which supports the grinding wheel, thereby obviating the necessity of a separate and independent source of power for operating the blower.

A still further object of the invention is to provide an attachment for dental hand pieces which is capable of performing the functions above set forth, and which is at the same time extremely simple in construction, light in weight, compact and inexpensive to manufacture.

In addition to the foregoing, this invention comprehends improvements in the details of construction and arrangement of parts, to be hereinafter described and particularly set forth in the appended claims.

In the accompanying drawings in which similar and corresponding parts are designated by the same characters of reference throughout the several views in which they appear.

Figure 1 is a view in side elevation of a dental hand piece of conventional type illus-

trating the association therewith of my invention.

Fig. 2 is a view of the dental hand piece and associated part illustrating the receptacle partly in section.

Fig. 3 is a view, partly in section taken on the line 3—3 of Fig. 2.

Fig. 4 is an end view of the attachment and

Fig. 5 is a transverse section taken on the line 5—5 of Fig. 3.

With reference to the drawings, 10 indicates a hand piece of conventional type including the chuck 11 in which the spindle 12 is held, the latter supporting a grinding wheel 13 upon its outer end. The chuck 11 includes a small set screw 14 which forms no part of this invention, but which is utilizable in some measure to secure in place a conical sleeve 15 which surrounds the chuck, 70 said sleeve having a small slot 16 in which to receive the screw 14. The sleeve is thus securely held against rotation. Mounted upon the sleeve 15 is a plate 17 having a lug 18 formed therewith to be received between 80 a pair of lugs 19 which are formed integrally with a circular plate 20 forming part of the suction apparatus to be described. Secured to the plate 20 is a cylindrical casing 22 forming the blower or suction casing which is 85 formed with a central and forwardly extending nipple 23 to which a shield 24 may be attached. The shield 24 comprises a casing portion 25 to partly inclose the grinding wheel, and said casing terminates in a conical extension 26 which is applied to the extension 23 and held thereon by friction or some positive means. The plate 20 is formed with an enlarged central bearing 27 in which a shaft 28 is journaled. The inner end of the shaft 95 carries a fan 29 of conventional type. Mounted upon the outer end of shaft 28 is a relatively small pinion 30 which is in meshing engagement with a relatively large pinion 32 which is adapted to be mounted upon 100 the spindle 12 of the grinding wheel. The pinion 32 may be either formed so as to be removably applied to the spindle, or it may be formed integrally with the spindle as desired. As stated above, the lugs 18 and 105 19 are interfitting, and are apertured to receive a bolt 33 which is formed at one end with a handle 34, a nut 35 being applied to the other end. A lug 36 is formed integrally with one lug 19 so as to hold the nut 35 110

against rotation. Extending tangentially from the casing 22 is an outlet conduit 37 which is curved rearwardly and formed with a flange 38 to which the flange 39 of a cylindrical perforated casing 40 is applied. The flange 39 may have radial lugs 41 to enter the recesses of enlargements 42 formed upon the flange 38 whereby the casing 40 may be secured to the extension 37 by applying the 10 same thereto and by rotating the casing 40 slightly to cause interengagement of the enlargements 42 and lugs 41.

The bag 43 of fabric or the like is inclosed within the casing 40 and the mouth of the 15 bag is caught between the flanges 38 and 39, thereby establishing communication between the interior of the bag and the interior of the blower casing 22.

From the foregoing description it will be 20 obvious that rotation of the spindle 12 will be communicated through the pinion 32, and pinion 30 to the blower shaft 29, setting the latter in rotation at a relatively high rate of speed whereby to create a suction through 25 the shield 24, expelling the air through the curved extension 37 into the bag 43 which becomes distended. During the act of grinding porcelain teeth, gold crowns or other work the particles which are released will 30 be caught in the current of air traveling inwardly through the shield 24 and carried into the bag 43 and retained therein. Thus, the gold particle driven off during the act 35 of grinding the gold crowns or other work formed of precious metals, and which particles have hitherto been lost, may now be collected in the bag 43 and subsequently recovered. It will also be apparent, that since 40 all particles are collected, the act of grinding with this apparatus is rendered safe to the operator, since heretofore the particles driven off have been breathed in by the operator, thereby resulting in discomfort and pulmonary diseases. When the spindle 12 is 45 to be inserted in the chuck 11, or when one spindle or grinding wheel is to be substituted for another the handle 34 is swung so as to release the bolt 33, thereby permitting the blower casing, shield 24 and casing 40 50 to be thrown back in an arc of a circle about the bolt 33 as a center. The pinions 30 and 32 will thus be disengaged, and obviously when the blower is returned to normal position the pinions will automatically be reengaged. I provide a flange 31 on the outer 55 end of the gear 30, to engage the outer face of the pinion 32. Thus, the flange 31 prevents the accidental displacement of the sleeve 15 from the chuck, the set-screw 14 60 acting conjointly to prevent rotation of the sleeve. As an additional protection to the hand of the operator I provide a disk 45 forming part of the shield 44, and located rearwardly of the pinion 32, said disk having a central opening to receive the spindle. 65

The shield 44 it will be noted forms part of the sleeve 15 and serves to partly inclose the pinion 32.

With a slight variation my invention may be applied to a dental lathe used in the laboratory in which event the spindle 12 is driven directly from the motor shaft or other rotating part of the lathe, and the shield 25 is used to partly inclose the grinding wheel or other tool used upon the lathe. The conventional type of lathe employed for dental purposes merely comprises a motor, the shaft of which is extended to receive the grinding wheel or other tool to be used. My device would be provided with a base to be attached 70 to the base upon which the motor rests. The blower or suction apparatus would then be driven by means of a belt from a pulley on the motor shaft. 75

Thus, it will be obvious that I have provided a useful adjunct to a dental engine or lathe whereby not only is the health of the operator protected by its use, but also to effect a saving of precious metals which has heretofore been a source of loss to the dentist 80 and dental manufacturer. It will furthermore be apparent that there is no separate source of power required to operate the suction apparatus, the power being derived directly from the spindle of the hand piece in 85 the case of the dental engine, or the motor shaft in the case of the lathe. Since the device may be constructed largely of aluminum, it will not add considerable weight to the hand piece, and since it is relatively 90 small in size it will not form an obstruction to the use of the hand piece in the ordinary manner. Other uses and advantages will readily occur to those skilled to the art to 95 which this invention appertains. 100

While I have illustrated and described my invention with some degree of particularity, I realize that in practice various alterations therein may be made. I therefore reserve the right and privilege of changing the form 105 of the details of construction or otherwise altering the arrangement of the correlated parts without departing from the spirit of the invention or the scope of the appended claims. 110

Having described my invention, what I claim as new and desire to secure by United States Letters Patent is:

1. In combination with a dental hand piece, a sleeve to encircle the same, a lug formed on 120 said sleeve, a second lug pivotally connected to the first, and a shield, blower casing and receptacle mounted on said second lug for movement relative to the hand piece.
2. In combination with a dental hand 125 piece, means for embracing the same, a blower casing and shield in connection therewith to receive the tool mounted in the chuck of the hand piece, and means for pivotally connecting said blower casing to the 130

- hand piece embracing means whereby to permit movement of the casing and shield away from the tool to permit adjustment of the latter.
- 5 3. In combination with a dental hand piece, a sleeve to encircle the chuck, a blower casing pivotally mounted on the sleeve, a shield connected to the blower casing to receive a tool mounted in the chuck, 40 and a casing to receive waste material secured to the blower casing and normally extending parallel to the hand piece when a device is in use, the casing being movable to a position substantially at right angles to the 45 hand piece to remove the shield from the tool to permit adjustment of the latter.
- 10 4. In combination with a dental hand piece, a sleeve to encircle the chuck thereof, an apertured lug formed on said sleeve, a blower casing including an end plate, an 50 apertured lug formed on said end plate, a bolt entering said lug to pivotally mount the blower casing, a shield secured to the blower casing, said blower casing having a lateral curved outlet, a cylindrical casing of 55 rigid material secured to the outlet and extending normally parallel to the hand piece in spaced relation thereto, and a bag of fabric held within the cylindrical casing in communication with the outlet.
- 15 5. In combination with a dental hand piece, a sleeve for encircling the chuck thereof, a tool spindle inserted in the chuck, a gear mounted on said spindle, a blower casing 60 pivotally mounted on the sleeve, a gear wheel forming a part of the blower mechanism, a disk forming part of said second 65 gear to engage the rear face of the first gear to prevent accidental dislodgement of the sleeve when the gears are in mesh, and a shield forming part of the casing to encircle a tool held upon the spindle.
- 20 6. In combination with a dental hand piece, a sleeve to encircle the chuck, a tool spindle mounted in the chuck, a gear wheel 45 mounted on the spindle, a shield forming part of the sleeve to encircle said gear, a plate forming part of the shield and disposed in spaced relation to the gear, a blower casing and blower mechanism pivotally 50 mounted on the sleeve, a gear wheel forming part of the blower mechanism, a disk secured to the rear face of said second gear and extending beyond the periphery thereof to enter the space between the first gear and the plate, and a shield forming part of the blower casing to receive a tool mounted upon the spindle.
- 25 7. A dental apparatus including a sleeve, a blower casing having an inlet, and a tangential outlet, a shield frictionally held upon the inlet, means for pivotally mounting the blower casing upon the sleeve, a blower within the casing, a gear for operating the blower mounted exteriorly of the casing, 55 and a casing of rigid material secured to the outlet of said blower casing.
- 30 In testimony whereof I affix my signature in presence of two witnesses.
